UNITED STATES PATENT OFFICE.

MICHELLAN C. FULLENLOVE, OF TOLEDO, OHIO, ASSIGNOR OF ONE-HALF TO PERITZ JACOB, OF TOLEDO, OHIO.

LOCK MECHANISM.

Application filed April 22, 1926. Serial No. 103,925.

This invention relates to an improvement in lock mechanisms and more particularly to a lock mechanism for use in connection with safe locks to prevent rotation of the 5 spindle for the bolt retracting mechanism of such a lock, in the event of an incorrect manipulation of the tumbler dial or an attempt to break off the said dial by force, or an attempt to blow the safe or drill the door there- 10 of, and while the invention is primarily designed for use in this connection, it may be employed wherever it is desired to prevent unlicensed movement of a rotary or 15 slideable part.

More specifically, it is one of the objects of the present invention to provide locking mechanism interposed between the tumblers of a safe lock and the spindle for the bolt retracting devices and constructed to be actuated through improper manipulation of 20 tumbler dial to effect the automatic projection of a locking member into engagement in a seat in the said spindle so as to prevent rotation of the spindle through the manipulation of the handle thereof, to actuate the 25 said bolt retracting devices, so that one unfamiliar with the combination of the lock for the safe and attempting to determine the combination by manipulation of the tumbler 30 dial, will fail to accomplish this result.

Another object of the invention is to so construct the locking mechanism for the said bolt retracting spindle as to effect projection of the locking element into engagement with the spindle in the event any attempt is made 35 to forcibly disturb the tumbler dial or drill the door of the safe, or open the door by the use of explosives.

Safety locking mechanisms designed for 40 the purpose of preventing surreptitious opening of safe doors are ordinarily of a purely mechanical nature and are not always efficient and, therefore, it is a further object of the present invention to provide 45 a mechanism of this class embodying a vacuum chamber, a fluid-tight expansible and contractible actuating unit within the chamber containing a gaseous fluid and normally expanded through the sustained expansion of the fluid due to the pressure difference between the fluid and the vacuum, 50 and means actuated through contraction of the said unit, upon destruction of the vacuum, for effecting actuation of the locking 55 element of the mechanism, so that the mech-

anism is not dependable, for its operation, primarily upon the actuation of mechanical parts which are subject to disarrangement.

In the accompanying drawings:

Figure 1 is a plan view of the safety locking mechanism embodying the invention, installed upon a safe door, parts being shown in section.

Figure 2 is a vertical transverse sectional view taken substantially on the line 2—2 of Figure 1, looking in the direction indicated by the arrows, the parts being shown on an enlarged scale.

Figure 3 is a view similar to Figure 2, but illustrating the parts in the positions which they will assume upon destruction of the vacuum in the vacuum chamber.

Figure 4 is a vertical transverse sectional view taken substantially on the line 4—4 of Figure 2, looking in the direction indicated by the arrows.

Figure 5 is a horizontal sectional view taken substantially on the line 5—5 of Figure 2, looking in the direction indicated by the arrows.

In the drawings, the numeral 1 indicates in general a safe door mounted in the usual manner in the door opening in the front wall 2 of the safe, and except in a certain respect to be presently explained, the door is of the ordinary construction. The numeral 3 indicates the dial knob for adjusting the tumblers of the ordinary lock mechanism and which tumblers are indicated by the numeral 4, and the numeral 5 indicates the spindle which supports and coacts with the mechanism for retracting the locking bolts which, however, are not shown as they constitute no part of the present invention.

The spindle 5 is provided at the exterior of the door with the usual handle 6 whereby it may be rocked in its bearing in the door to actuate the said bolt retracting devices. The tumblers 4 do not differ from the ordinary tumblers except that the rearmost one is provided in its periphery with a notch 7 supplemental to the notch which is to receive the head of the usual locking lever of the lock mechanism (not shown) and the next adjacent tumbler is provided in its periphery with a similar notch 8. The numeral 9 indicates a detent which is mounted for rocking movement between its ends upon a pivot pin 10 mounted upon the inner side of the door 1 and is provided at one end with a

lug 11 designed to enter the notches 7 and 8 in the two tumbler discs when the said tumbler discs are in position with their notches substantially in registration. The purpose of the detent 9 will presently be explained but at this point it may be stated that the notch 8, as shown in Figure 1, is located at such point on the periphery of the respective tumbler disc that while, when the notch 7 is beneath the lug 11 of the detent, and the dial is at such time in the position necessary to effect the positioning of the tumbler disc to bring the other or usual notch of the disc into position to receive the head of the locking lever of the lock mechanism, the said notch 8 will be slightly out of registration with the notch 7 and, therefore, the lug 11 will engage the periphery of the tumbler disc in which the said notch 8 is formed and will be prevented from entering the notch 7. However, it is contemplated that rotation of the tumbler adjusting dial 3 past the proper position to bring the usual notch of the tumbler disc in which the notch 8 is formed, into position to receive the head of the locking lever of the lock mechanism, will so position the last mentioned tumbler disc that the lug 11 may enter the notches 7 and 8, these notches being at such time in substantial registration or opposite each other. A spring 12 is mounted at one end upon a pin 13 upon the inner side of the door of the safe and bears between a stop pin 14 and the upper side of the detent 9 at that end of the detent at which the lug 11 is located, and this spring yieldably holds the said lug of the detent in contact with the peripheries of the tumbler discs.

The numeral 15 indicates in general a vacuum chamber which is securely mounted upon the inner side of the door of the safe and comprises a rear wall 16, a front wall 17, end walls 18 and 19, a top 20, and a bottom 21. This chamber is exhausted of air so that a vacuum is created therein, and the chamber is, of course, hermetically sealed. A thin frangible plate 22, of glass or other frangible material, is mounted and sealed in an opening 23 in the top 20 of the vacuum chamber. The numeral 24 indicates a percussion member which is pivotally mounted upon a pin 25 fixed upon the inner side of the safe door or suitably mounted upon the top of the vacuum chamber, as may be preferred, and a spring 26 is coiled about the pin 25 and is connected at one end to the said pin and at its other end is engaged, as at 27, behind one edge of the said percussion member, as best shown in Figure 2 of the drawings. The percussion member is provided at its free end with a tooth 28, and the under side of the detent 9, at the end opposite its end which carries the lug 11, is formed with a notch 29 in which the said tooth is

normally engaged, as shown in the said Figure 2, so that so long as the lug 11 is in engagement with the un-notched peripheral portions of the tumbler discs, the detent will be held in such position as to restrain the percussion member from rotative movement about the pivot pin 25 under the influence of the spring 26. Near its toothed end 28, the percussion member is provided with a piercing point indicated by the numeral 30 and the parts are so arranged that at the instant the lug 11 engages in the notches 7 and 8 in the tumbler discs, the spring 12 will act to rock the detent about its pivot pin and disengage it from the toothed end of the percussion member, whereupon said member will be sharply swung about its pivot and its piercing point 30 will be driven through the frangible element 22. At this moment there will be an inrush of air into the vacuum chamber 15, thus destroying the vacuum, and this produces a result which will be made clear after the following description of certain mechanism which is enclosed within the vacuum chamber.

The spindle 5, through the rotative movement of which the devices for retracting the locking bolts of the lock are actuated, does not differ from the ordinary spindle except that it is provided in one side and opposite the end wall 8 of the vacuum chamber, with a socket 31 which, when the spindle is in normal position, directly opposes the said end wall of the vacuum chamber and is located directly opposite a small pane of glass or other frangible material indicated by the numeral 32, which is sealed in a fluid-tight manner, in an opening 33 in the said end wall 18 of the casing. A locking bolt 34 is slidably mounted in suitable bearings 35 upon the rear wall 16 of the chamber and has one end engaging or substantially engaging against the inner side of the frangible pane 32 and the said bolt is provided at its other end with a lug 36 or other stop element for engagement with the adjacent one of the bearings 35 to limit the movement of the bolt. At this point it will be evident that when a blow is struck against the lug-carrying end of the bolt it will be shifted laterally, fracturing the frangible element 32 and in this manner its outer end will be projected into the socket 31 so as to effectually prevent rotative movement of the spindle 5 and actuation of the devices for retracting the locking bolts of the safe lock. The numeral 37 indicates a percussion member which is rotatably mounted at one end upon a pin 38 within the vacuum chamber and a spring 39 is arranged upon the said pin 38 and coacts with the said percussion member 37 to sharply and forcibly swing the said member upwardly and to the left in Figure 2, to strike against the end of the locking bolt 34 and cause shifting movement of the said bolt in

the manner above explained to cause its other end to engage in the socket 31 in the spindle 5. The percussion member 37 is normally held in an inactive position through the medium of a detent which is indicated in general by the numeral 40 and which is mounted between its ends upon a pivot pin 41 and normally assumes the position shown in Figure 2, in which position its lower end will engage over the free end of the percussion member 37 to hold the member normally in the position shown in the said figure. A stop pin 42 is preferably arranged within the vacuum chamber and is engaged by one side of the detent 40 above the pivot 41 so that normally the detent will assume a definite position with relation to the percussion member restraining the latter from actuation by the spring 39.

The numeral 43 indicates in general an actuating unit which is likewise housed within the vacuum chamber and which comprises a hollow substantially tubular body 44 of some flexible and somewhat resilient material such for example as soft rubber and preferably provided with circumferential corrugations 45 whereby it will have a tendency to contract after expansion, the said tubular body being connected in an air-tight manner at one end to a head 46 which is fixedly mounted within the vacuum chamber adjacent the end wall 18 thereof. The other end of the tubular member 45 is connected in an air-tight manner with a head 47 to which is secured one end of a stem 48 which works slidably through openings in bearings 49 fixed within the vacuum chamber. The end of the stem 48 which is remote from the head 47 is provided with an opening 50 into which the upper end of the detent 40 projects. At this point it will be evident that inasmuch as the tubular body 44 of the actuating unit contains a volume of air and is hermetically sealed and the chamber 15 is evacuated of air, the said body will be normally expanded against its tendency to contract and due to the provision of the corrugations, expansion is chiefly in a longitudinal direction so that a longitudinal thrust is exerted against the stem 48 so as to hold the detent 40 in the active position shown in Figure 2. However, when the frangible pane 22 is fractured by the piercing point 30 of the percussion member 24 and air is permitted to enter the said chamber, the body 44 will contract and a pull will be exerted upon the stem 48 to rock the detent 40 substantially to the position shown in Figure 3, thereby disengaging its lower end from the percussion member 37 and permitting the spring 39 to actuate this member to cause the same to strike against the inner end of the locking bolt 34, fracture the frangible element 32 and project the outer end of the locking bolt into the socket 31, thereby effectually locking the

spindle 5 against rotation. In this latter position of the detent 40 its upper portion will rest against a stop pin 51 arranged within the vacuum chamber opposite the pin 42.

It will be understood, of course, that the actuating member 43 may be of some construction other than that illustrated in the drawings and above described, so long as it is expansible and contractile and contains a gaseous fluid such as air and is normally expanded through the sustained expansion of the fluid, due to the pressure difference between the fluid and the vacuum within the chamber.

As previously stated, the invention contemplates the provision of means for effecting operation of the locking mechanism in the event an attempt is made to force the tumbler dial 3 from the door or otherwise attempt to open the door by force, and with this end in view, the door is provided with a front plate 52 which is preferably of the same marginal dimensions as the front of the door and is slightly outwardly bulged from its marginal portions so that except for its marginal portions, the plate is slightly spaced from the face of the door, as clearly shown in Figure 1 of the drawings. A pane 53 of glass or other frangible material is sealed in an opening 54 formed in the front wall 17 of the vacuum chamber, and a piercing pin 55 is secured at its outer end to the inner side of the front plate 52, as indicated by the numeral 56, and extends slidably through an opening 57 formed in the body 100 of the door, the inner end of the pin being in contact, or substantially in contact with said frangible pane 53. It will now be evident that if force should be exerted against the front plate, as for example in an attempt to strike the dial 3 from its spindle or if an attempt should be made to forcibly drill through the door or if other force is applied to the face of the door in an attempt to open the same, the pin 55 will be driven rearwardly through the opening 57 and will fracture the frangible pane 53, thereby admitting air in sufficient volume into the vacuum chamber to destroy the vacuum and effect operation of the mechanism within the said chamber to project the bolt 34 to locking position.

In order that, when the bolt 34 is projected to engage at its end in the socket 31 and lock the spindle 5 against rotation, an alarm may be sounded automatically, means is provided which will now be described. The said means comprises a pair of spaced contacts 58 mounted upon an insulating base 59 preferably located upon the bottom 21 of the vacuum chamber, a wire 60 being led from one of the contacts to a source of current supply indicated by the numeral 61, and a wire 62 being led from the other contact to one binding post of an electric bell 63, the

other binding post of the bell being connected by a wire 64 with the other terminal of the source of current supply. The contacts 58 are located in the path of movement of a contact bridging finger 65 which extends downwardly from the locking bolt 34 and which is designed to enter between the contacts 58 when the said locking bolt is struck into engagement in the socket 31 through impact by the percussion member 37. Therefore, at the time the locking bolt 34 is actuated to lock the spindle 5, an alarm will be sounded.

Having thus described the invention, what I claim is:

1. In lock mechanism, a vacuum chamber, a fluid-tight expandible and contractible actuating unit within the chamber containing a gaseous fluid and normally expanded through the sustained expansion of the fluid due to the pressure difference between the fluid and the vacuum, a locking member within the chamber supported for projection through a wall of the chamber to engage a part to be locked, and means interposed between the said actuating unit and the locking member operable to actuate the member upon contraction of said unit upon the admission of air into the chamber.
2. In lock mechanism, a vacuum chamber, a fluid-tight expandible and contractible actuating unit within the chamber containing a gaseous fluid and normally expanded through the sustained expansion of the fluid due to the pressure difference between the fluid and the vacuum, the chamber having an opening in one of its walls, a frangible closure for said opening, a locking member within the chamber supported for projection through the opening to engage a part to be locked, and means interposed between the said actuating unit and the said locking member operable to actuate the member upon contraction of the said unit upon the admission of air into the chamber.
3. In lock mechanism, the combination with a permutation lock including a tumbler disc, and the rotatable spindle of the bolt retracting mechanism of said lock, of a vacuum chamber arranged in juxtaposition to the said disc and spindle, a fluid-tight expandible and contractible actuating unit within the chamber containing a gaseous fluid and normally expanded through the sustained expansion of the fluid due to the pressure difference between the fluid and the vacuum, a locking member within the chamber supported for projection through a wall of the chamber to engage the spindle and lock the same against rotation, means interposed between said actuating unit and the said locking member operable to actuate the member upon contraction of the unit upon the admission of air into the chamber, and means operable upon rotation of the tumbler disc

to a predetermined position, to fracture a portion of a wall of the chamber and permit the entrance of air.

4. In lock mechanism, the combination with a permutation lock including a tumbler disc having a notch in its periphery, and the rotatable spindle of the bolt retracting mechanism of the lock, of a vacuum chamber arranged in juxtaposition to the said disc and spindle, a fluid-tight expandible and contractible actuating unit within the chamber containing a gaseous fluid and normally expanded through the sustained expansion of the fluid due to the pressure difference between the fluid and the vacuum, a locking member within the chamber supported for projection through a wall of the chamber to engage the spindle and lock the same against rotation, means interposed between the said actuating unit and said locking member operable to actuate the member upon contraction of the unit upon admission of air into the chamber, one wall of the chamber having a frangible portion, a spring actuated percussion member supported for movement to position to fracture said portion of the wall of the chamber, and a detent for the percussion member normally restraining the same from such movement and having a portion normally contacting the un-notched portion of the periphery of the said tumbler disc and movable to release the percussion member upon engagement of its said portion in the notch of the disc.

5. In lock mechanism, the combination with a permutation lock including a tumbler disc having a notch in its periphery, and the rotatable spindle of the bolt retracting mechanism of the lock, of a vacuum chamber arranged in juxtaposition to the said disc and spindle, a fluid-tight expandible and contractible actuating unit within the chamber containing a gaseous fluid and normally expanded through the sustained expansion of the fluid due to the pressure difference between the fluid and the vacuum, a locking member within the chamber supported for projection through a wall of the chamber to engage the spindle and lock the same against rotation, means interposed between the said actuating unit and said locking member operable to actuate the member upon contraction of the unit upon admission of air into the chamber, one wall of the chamber having a frangible portion, a spring actuated percussion member supported for movement to position to fracture said portion of the wall of the chamber, a detent for the percussion member normally restraining the same from such movement and having a portion normally contacting the un-notched portion of the periphery of the said tumbler disc and movable to release the percussion member upon engagement of its said portion in the notch of the disc, and a spring coating with

the said detent and yieldably holding the same in active relation to the disc.

6. In lock mechanism, the combination with a permutation lock including a tumbler disc having a notch in its periphery, and the rotatable spindle of the bolt retracting mechanism of the lock, of a vacuum chamber arranged in juxtaposition to the said disc and spindle, a fluid-tight expansible and contractible actuating unit within the chamber containing a gaseous fluid and normally expanded through the sustained expansion of the fluid due to the pressure difference between the fluid and the vacuum, a locking member within the chamber supported for projection through a wall of the chamber to engage the spindle and lock the same against rotation, means interposed between the said actuating unit and the said locking member operable to actuate the member upon contraction of the unit upon the admission of air into the chamber, the said chamber having an opening in one wall, a frangible closure for the opening, a percussion member mounted for movement to position to fracture the said closure, a spring urging the said member to such position, a pivoted detent having a portion at one side of its pivot contacting the periphery of the said tumbler disc, the said detent having a tooth at the other side of its pivot to engage the said percussion member and retain the same in an inactive position, the engagement of the said portion of the detent in the notch in the tumbler disc permitting movement of the detent to release the percussion member, and means yieldably holding the detent in engagement with the disc.

7. In lock mechanism, a vacuum chamber, a fluid-tight expansible and contractible actuating unit within the chamber containing a gaseous fluid and normally expanded through the sustained expansion of the fluid due to the pressure difference between the fluid and the vacuum, a locking member within the chamber supported for projection through a wall of the chamber to engage a part to be locked, means interposed between the said actuating unit and the said locking member operable to actuate the member upon contraction of the unit upon the admission of air into the chamber, the said means comprising a percussion member, means urging the same for percussive contact with the locking member to actuate the same, and a detent coacting with the percussion member to maintain the same in inactive position and operatively con-

nected with the actuating unit, for movement thereby to release position.

8. In lock mechanism, a vacuum chamber, a fluid-tight expansible and contractible actuating unit within the chamber containing a gaseous fluid and normally expanded through the sustained expansion of the fluid due to the pressure difference between the fluid and the vacuum, a locking member within the chamber supported for projection through a wall of the chamber to engage a part to be locked, and means interposed between the said actuating unit and the said locking member operable to actuate the member upon contraction of the said unit upon the admission of air into the chamber, the said means comprising a percussion member pivoted for swinging movement in the direction of the locking member for percussive contact therewith, a spring urging the percussion member in such direction, a pivoted detent engaging at one end with the said percussion member to maintain the same in inactive position, and operative connection between the other end of the detent and the said actuating unit.

9. In lock mechanism, the combination with a door to be locked, and locking mechanism for the door including a movable actuating element, of a face plate upon the face of the door having a portion spaced therefrom, a vacuum chamber upon the inner face of the door, a fluid-tight expansible and contractible actuating unit within the chamber containing a gaseous fluid and normally expanded through the sustained expansion of the fluid due to the pressure difference between the fluid and the vacuum, a locking member within the chamber supported for projection through a wall of the chamber to engage the said movable actuating element of the door locking mechanism, to prevent movement thereof, means interposed between the said actuating unit and the said locking member operable to actuate the member upon contraction of the said unit upon the admission of air into the chamber, the chamber having an opening therein, a frangible closure for the opening, and a force-transmitting element slidable through the said door and having one end presented to the frangible closure and movable in the direction of the said frangible closure to fracture the same upon inward displacement of the face plate of the door in the direction of the door.

In testimony whereof I affix my signature.

MCCLELLAN C. FULLENLOVE. [L.S.]
